UNITED STATES PATENT OFFICE.

SPENCER C. CARY, OF BROOKLYN, NEW YORK.

SHIPPING-CASE.

1,325,555.

Specification of Letters Patent. Patented Dec. 23, 1919.

Application filed October 27, 1911, Serial No. 657,077. Renewed March 15, 1919. Serial No. 282,959.

To all whom it may concern:

Be it known that I, SPENCER C. CARY, a citizen of the United States, residing in the city of New York, borough of Brooklyn, county of Kings, and State of New York, have invented a certain new and useful Shipping-Case, of which the following is a specification.

This invention is a case for shipping 10 various articles, more particularly containers for oil and the like.

It is a common practice in the transportation of oil, or other liquids, to place the same in cans of about five gallons (5 gals.) 15 capacity, and to incase two of said cans within an inclosing package of one form or another, said casing being composed usually of walls of wood or wood veneer nailed together and bound with metal box 20 strapping.

By reason of the weight of the cans, a wooden casing having its walls nailed together is too frail to successfully withstand the strain of the weight and the handling 25 to which the package is subjected. To strengthen the case, it has been customary to employ metal box strapping, composed of wire or sheet metal, but even this expedient has been found unsatisfactory. As 30 a result there exists a demand for a strong, durable and economical packing case, especially adapted for the transportation of heavily loaded oil cans, and to meet this demand is the object of this invention.

In carrying out the invention, I employ 35 a sheet of metal of the size and form required to form the bottom, side walls and top of the packing case. This sheet is prepared in advance of the operation of assembling it with wooden end walls to complete 40 the inclosure for a plurality of oil cans, the preliminary preparation of the metal sheet consisting in cutting it to the form and dimensions required and, also, 45 in subjecting the sheet to the action of a powerful press in order to emboss the sheet at certain defined places for the purpose of producing panels in said sheet. The panels extend transversely with respect to 50 the sheet, and inwardly thereof, and they serve the purposes of stays in rendering the sheet strong and stiff enough to resist the weight and pressure of the filled cans, the latter being adapted to contact with the 55 pressed-in portions of the panels. When the cans are to be incased, a prepared metal

sheet is selected, and it is bent or folded at well defined lines, to form the bottom, two side walls and the top of the case, and wooden end pieces are inserted into the open 60 ends of the metal case, after which the end edges of the metal case are fastened to said end pieces, by any suitable means, such as by nails or screws. If desired, the end edges of the metal case may be flanged and 65 inserted or embedded into the material of the end pieces. The top of the case is formed by bringing the edges of the metal sheet into overlapping relation and by fastening the lapping edges, as by riveting 70 them together.

The invention embodies, also, means for separating the two cans adapted to be inclosed within the case. In one form of construction, the bottom of the sheet metal case 75 is doubled to produce a rib between certain panels, but in another form I employ a stay made separate from the sheet metal blank. The stay is composed of strong strap metal positioned in contact with the 80 bottom, sides and top of the sheet metal case, the end portions of the stay being inserted through the lapping edges of the sheet metal, and then bent upon said edges. The stay operates as a separator for the 85 cans, and it adds materially to the strength and rigidity of the sheet metal, so as to preclude to a large extent the tendency of the sheet metal to bend and buckle when the case is struck by an outside blow. 90

Other features of the invention and the advantages thereof will appear in the course of the following description taken in connection with the drawings.

In the accompanying drawings, I have 95 illustrated different practical embodiments of the invention, but the constructions shown therein are to be understood as illustrative, only, and not as defining the limits of the invention.

Fig. 1 is a plan view of a metal blank adapted to be bent so as to form the bottom, sides and top of a shipping case in accordance with this invention.

Fig. 2 is a vertical cross section through 105 a shipping case, the body of which is formed by the blank of Fig. 1.

Fig. 3 is a longitudinal section on the line 3—3 of Fig. 2.

Fig. 4 is a plan view of another form of 110 blank embodying the general features of the blank shown in Fig. 1, and in addition

thereto said blank of Fig. 4 is provided with an integral rib on the bottom of the resulting case, which rib acts as a separator for containers or cans adapted to be inclosed by the case.

Figs. 5 and 6 are a vertical cross section and a vertical longitudinal section of the shipping case having its body composed of the blank shown in Fig. 4.

10 Fig. 7 is a plan view of another form of blank adapted to form the body of the shipping case.

Figs. 8 and 9 are views in vertical cross section and vertical longitudinal section, respectively, of a packing case body resulting from the employment of the blank of Fig. 7.

15 Fig. 10 is a plan of a pressed metal blank embodying the panel construction of Fig. 1 and the flanged and slotted construction of Fig. 7 whereby the resulting metal case is adapted for the reception of the stay strap disclosed in Figs. 8 and 9.

20 Figs. 11 and 12 are cross sections of the metal case resulting from the bending of the blank shown in Fig. 10 and the use of the stay strap in connection therewith.

The body of the packing case is produced by bending a blank, A, of sheet metal at a number of points to form the bottom, sides 30 and top. This blank consists, preferably, of a single piece of sheet metal having the required form and dimensions. The blank is adapted to be bent on transverse lines indicated at *a*, *b*, *c*, and *d*, and, if desired, the 35 lines of bend may be indicated in any desired way on the sheet metal blank, as for example, by score marks, perforations, upset portions of the metal, etc. The bottom of the shipping case is adapted to be produced 40 by that part of the blank between score lines, *a* and *b*. One side wall of the case is formed by that part of the blank between *b* and *d*. The other side wall of the case is produced by that part of the blank between lines *a* and 45 *c*, and the top of the case is formed by bringing the end portions of the blank into lapping relation.

50 For the purpose of stiffening the body of the case, and of imparting sufficient rigidity to said case to withstand the weight of the contents and the strain of handling the case, the body portion thereof is provided with a number of panels which are produced in the sheet metal blank prior to the operation of 55 bending it to form the case. As shown, the bottom portion of the case is provided with a series of panels, B, preferably, four in number: each side wall has a plurality of panels, C, two of said panels being provided 60 on each side wall, and the top of the case, produced by the meeting ends of the blank, is provided with panels, D, preferably two in number. The sheet metal blank, A, is cut to the required form and size, and then 65 it is placed in a powerful press, which oper-

ates upon the sheet for the purpose of pressing or displacing the metal so as to result in the formation of the panels, substantially as hereinbefore described. The panels extend transversely of the sheet metal blank, but 70 they terminate within the side edges of the sheet, or the open ends of the resulting case body.

75 While I have shown and described the bottom of the case as having four panels, and the side of the case as having two panels each, it will be manifest that the number and arrangement of the panels may be varied within wide limits. It is deemed preferable, however, to provide the bottom of the body 80 with a sufficient number of panels which will secure very great strength and stiffness at the place where the case is subjected to the greatest strain. Furthermore, the panels, C, on the sides of the case serve to stiffen the 85 body so as to prevent the case from bending or buckling under the effect of blows which strike the outside of the case.

90 It will be understood that a desired number of sheet metal blanks, A, may be rapidly and economically produced from sheet metal at a factory, and prior to the operation of making the shipping case. The pieces of sheet metal are prepared in any suitable or desired way by cutting the sheets to the required form and dimensions, and thereafter subjecting the sheets to pressure in a suitable press which will emboss the sheets so as to produce the panels, B, C, and D thereon. The sheets having been prepared as described, they are packed in a flat condition 95 so as to be shipped economically from the factory to the place at which it is desired to convert them into packing cases.

100 When it is desired to make a packing case, 105 a sheet metal blank, A, is bent or folded on the lines *a*, *b*, *c*, and *d*, thus producing a substantially rectangular inclosure or body, shown in Figs. 2 and 3, the ends of said body 110 being open. The operation of bending the sheet having been completed, the end edges of the sheet are brought into lapping engagement as shown in Figs. 2 and 3, said end edges being attached together if desired, although this is not essential. It now only 115 remains for the operator to apply the end closures or sections, E, F, to the open end of the sheet metal body. An end closure or section, E, is adapted to be placed in one end portion of the sheet metal body, and to be secured to said body by suitable fasteners, such as the nails, *e*, or if desired, screws or other fasteners may be substituted therefor. The filled cans or containers may now be placed within the body so as to rest upon 120 panels, B, of the bottom, and thereafter the other end closure or section, F, should be positioned within the opposite open end of the sheet metal body, said end closure or section, F, being secured in position by nails, 125 130

screws, or other devices, *f*, all as shown in Fig. 3.

It will be noted that the sheet metal body is adapted to be easily and quickly bent, and 5 the end closures or sections, *E*, *F*, may be easily placed into position and secured to the end portions of the body. Each end section may be composed of wood or other material, in one piece, if desired. The employment 10 of the two sections or closures adds to the stiffness and strength of the resulting case. The edges of the sheet metal body are fastened firmly to rigid end pieces, the fastenings being applied to the bottom, sides 15 and top of the packing case. The lapping ends of the sheet metal blank may be riveted together, or the side edges of the blank may be attached to the end sections at the top of the case, as shown in Fig. 12.

20 Another way of making the case is to bend the blank along lines, *a*, *b*, so as to produce the bottom and upstanding sides, and to then position the rigid end pieces, *E*, *F*, at the open ends of the sheet metal body, and 25 finally the sheet metal and the wooden end pieces are fastened together, leaving those portions of the top having panels, *D*, extending upwardly from the package. The oil cans or the containers are now placed within 30 the package, and finally the top portions of the blank are bent along the lines, *c*, *d*, so that their free edges will overlap, thereby completing the top, which top is fastened to the upper edges of end sections, *E*, *F*, where 35 by a completely closed case is produced for enveloping the oil cans or other containers.

It will be observed, by reference to Figs. 2 and 3, that panels, *B*, *C*, *D*, extend inwardly with respect to the case. Panels, *B*, 40 engage with the bottom of the oil cans or containers; panels, *C*, engage with the outer sides of the oil cans or containers; and panels, *D*, rest upon the top ends of the oil cans, whereby the cans do not contact directly 45 with the metal of the blank forming the body but are limited to engagement with the inwardly extending panels.

Sheet metal blank, *A'*, of Fig. 4 is similar in all substantial respects to the blank, *A*, 50 of Fig. 1, that is to say, said blank, *A'*, is provided with panels, *B'*, *C'*, *D'*, and it is adapted to be bent or folded on the lines, *a'*, *b'*, *c'*, *d'*, respectively. In addition to the panels, blank *A'* is provided with means 55 adapted to separate the two oil cans or containers which are to be placed within the packing case. Said separating means consists of a rib, *G*, provided on that portion of the blank which forms the bottom of the body. The rib is produced by folding or 60 bending the middle part of the blank upon itself, whereby the rib is made integral with the sheet metal blank. The rib extends transversely across the blank, and it is positioned intermediate the two middle panels, 65

B' of the bottom. As shown in Figs. 5 and 6, the rib extends inwardly above the bottom and above the panels, *B'*, thereof.

The mode of making the body by bending the blank on the lines, *a'*, *b'*, of securing 70 end sections, *E'*, *F'*, within the open ends of the sheet metal body, and of closing the top of the sheet metal body by bending it upon the lines, *c'*, *d'*, is the same as in the construction heretofore described in connection with Figs. 1 to 3, inclusive. The employment of the rib adds additional strength or stiffness to the bottom of the packing case, but the primary office of said rib is to separate the cans or containers adapted to be 80 placed within the case. The rib acts to confine one can between itself and the panels at one side wall of the case, and to serve a like purpose in retaining the other can between the other side wall of the case, whereby the 85 rib acts to preclude sliding displacement of the two cans within the shipping case.

In Figs. 7, 8 and 9 of the drawings, I have illustrated another embodiment of the invention, wherein the body of the case is 90 formed by a sheet metal blank, *A*², adapted to be bent or folded on the lines, *a*², *b*², *d*², so as to produce a sheet metal body, the ends of which are closed by solid pieces, *E*², *F*², the latter being secured in position by nails, 95 screws or other fasteners to the side edges of the sheet metal composing the body. Blank *A*² may be, and preferably is, provided with panels similar to the panels, *B*, *C*, *D*, of Fig. 1, for the purpose of stiffening the 100 metal composing the body, but in Fig. 7 these panels are omitted for the sake of clearness. The side edges of blank, *A*², are extended at certain lines, and these extended edges are bent for the purpose of producing 105 flanges, *g*. The flanges are adapted to be embedded or inserted into the edges of end pieces, *E*², *F*², as shown in Fig. 9, whereby the side edges of the sheet metal blank are attached firmly to the rigid end pieces. The 110 flanged side edges are thus embedded in the end pieces, which preclude them from projecting beyond the end pieces, thus overcoming any tendency of cutting the hands of the operator when handling the heavy packing 115 case.

In connection with blank, *A*², there is employed a stay, *H*, composed, preferably, of flat or strap metal. The metal of the stay piece is separate from the sheet metal blank 120 adapted to form the body, and this stay piece is shown as being positioned within the sheet metal body. The stay piece is bent to conform to the interior shape and dimensions of the body, and the ends of said stay piece are attached the lapping top portions of the sheet metal body. The attachment of the end portions of the stay to the lapping portions of the sheet metal body 125 may be effected in various ways, but in the 130

preferred construction; blank, A², is provided near its end portions with slots, i. When the end portions of the blank are folded to form the top and to bring said end portions into lapping relation as shown in Figs. 8 and 9, the slots, i, of one end portion register or aline with the slots, i, of the other end portion. Stay, H, is positioned within the body before the end portions of the blank 10 are bent to form the top, and when bending said end portions, the slots, i, thereof slip over upstanding portions, h, of stay H. After closing the top of the case in the manner described, the end portions of stay H 15 are passed through slots, i, and are bent or doubled upon the top, as shown at h in Figs. 8 and 9, whereby the ends of stay, H, are united rigidly to the lapping portions of the top. This construction produces a strong 20 and substantial closure for the top of the case, and the case is so securely closed that it cannot be opened or tampered with without leaving some evidence of the attempt to open the case.

25 The employment of stay, H, within the packing case serves two purposes: first, the stay increases the stiffness and rigidity of the bottom, sides and top of the case itself, and said stay serves the additional purpose 30 of a separator for the cans or containers adapted to be packed within the case, the stay thus serving the primary purpose of rib, G, in the construction of Figs. 4, 5 and 6.

35 In Figs. 10, 11 and 12 of the drawings there is shown a metal case formed by a metal blank A⁴ pressed to produce the panels B² C² D² similar to Fig. 1, which blank A⁴ is flanged at the edges, as at g², and the 40 ends of which are slotted at i². The blank is bendable as heretofore described to produce the bottom, sides and top of the case, the rigid end pieces E² are secured within the box by nailing the parts and by embedding 45 the flanges g² into said end pieces, and the box is interiorly stayed by a metal strap H², the latter being positioned in contact with the bottom, sides and top as described in connection with the metal case of Figs. 50 8 and 9. The ends of stay H² are inserted through the slots i² when the parts forming the top are brought into lapping relation, after which said ends of the stay are bent to 55 securely fasten the lapped meeting parts of the top, said interiorly positioned stay acting as a separator for the cans placed within the metal box.

Under some conditions the panels, D, D', 60 of the blanks shown in Figs. 1 and 4 may be constructed so that one panel will enter the other panel when the end edges of the blanks are brought into overlapping engagement when folding said blank to complete the top of the case. It is thought that 65 the operation and advantages of the inven-

tion will be understood by those skilled in the art, from the foregoing description taken in connection with the drawings. The sheet metal blank of one form or another, may be easily and quickly prepared, and all the blanks may be placed one upon the other so as to take up very little room when packing, shipping and storing the metal. The packing case may be easily and quickly formed by bending the blank as described, 70 and by attaching the rigid end pieces to the bent up body resulting from the bending of the blank. The case is simple and strong in construction, and it is economical to manufacture. The case is stayed or reinforced to withstand the weight of the packages to be inclosed therein, and said case is not liable to become broken or materially injured when handling the same. The employment of the stay, H, is a very material 80 advantage for the reason that said stay not only separates the oil cans or containers, but it adds materially to the stiffness and rigidity of the walls of the sheet metal body, besides affording a very convenient means for 85 securely closing the top of the case.

Having thus fully described the invention, what I claim as new, and desire to secure by Letters Patent is:—

1. A shipping crate embodying a blank 95 composed of sheet metal scored and bendable on predetermined lines to produce a body of a case, said blank being embossed transversely to form parallel panels throughout the central part thereof and to 100 leave a marginal edge of the blank free from embossing, the marginal edges being provided with flanges, end closures positioned within the open ends of the body produced by bending the blank, the flanges being embedded in the end closures, and means 105 passing through said marginal edges of the blank into the end closures for securing the end closures fixedly to the body.

2. In a shipping case, a body composed 110 of sheet metal bent to the required form, said sheet metal having integral panels, and a strap positioned in contact with the panels, a part of the walls of the body being bent to extend inwardly for a definite 115 distance from said walls for separating the articles adapted to be positioned within the case.

3. In a shipping case, a body composed 120 of sheet metal bent to produce the walls of the shipping case, said metal blank being embossed to produce panels integral with the bottom, and an article-separating strap positioned in contact with the inner surface 125 of the metal blank, the end portions of said strap being secured to the top of the case.

4. A shipping case embodying a body composed of sheet metal bent to produce the sides, bottom and top, the end portions 130 of said sheet metal being in lapping engage-

ment, end closures attached to said body, and a separate stay strap bent to be positioned in contact with said metal body, said stay strap being attached to the body of the lapping end portions of the sheet metal composing said body.

5. In a shipping case, a body composed of a sheet metal blank embossed to produce a series of panels, said blank being bent to 10 produce the bottom and sides, and the ends of said blank being lapped and perforated, combined with end members secured to said body, and a stay positioned in contact with said blank and the panels thereof, the respective 15 end portions of said stay being secured to the lapped portions of said blank by passing said ends of the stay through said lapped and perforated portions of the sheet metal and bending the protruding 20 portions of said ends to lock the stay and end portions against movement.

6. In a shipping case, a sheet metal body the margins of which are flat and in a common plane, said body being provided within 25 said margins with struck up panels, combined with end members the edges of which are in contact with said margins of the body and are fastened thereto.

7. In a shipping case, a sheet metal body 30 comprising a blank the smooth margins of which are in the same plane, said blank being provided with embossed panels positioned within said margins and extending from the plane of said sheet and the latter 35 being bendable on definite lines for producing the several walls of the shipping case, combined with end members secured to said smooth margins of the sheet or blank.

8. In a shipping case, a sheet metal body 40 comprising a single blank the margins of which are smooth and in a common plane, said blank being provided within the limits of said smooth margins with struck up panels extending beyond the plane of the 45 sheet, said blank being bendable for producing the several walls of the shipping case, combined with end members attached to and contacting with the smooth margins of the bent up blank, the panels of said 50 blank extending inwardly with respect to the walls of said body.

9. In a shipping case, a sheet metal body comprising a single blank the margins of which are smooth and in a common plane, 55 said blank being provided within the limits of said smooth margins with struck up panels, combined with end members attached to and contacting with said smooth margins of the body, said end members being substantially free from contact with said panels and said panels extending for appreciable distances inwardly from the walls so as to serve as contact members for the contents of the shipping case.

65 10. In a shipping case, a sheet metal body

comprising a single blank the margins of which are smooth and in a common plane, said blank being provided with a succession of struck up panels and said blank being bendable on definite lines for producing the 70 bottom, top and sides of the case, combined with end members attached to and contacting with the smooth margins of the body, the panels on the bottom of the body exceeding in number and being of less width 75 than the panels on the sides of the body.

11. In a shipping case, a sheet metal body comprising a single blank and margins of which are in a common plane with said blank, said blank being provided with 80 struck up panels positioned within the limits of said margins, combined with end members contacting with the margins of said body, the edges of said sheet metal blank being flanged and said flanges being 85 embedded in the material composing the end members.

12. In a shipping case, a sheet metal body comprising a single blank the margins of which are in a common plane and said blank 90 being bendable on definite lines to produce the several walls of the body, end members contacting with and attached to said margins of the body, and a stay strap positioned intermediate the end members and 95 contacting with the inner surfaces of said body, said stay strap being separate from the body.

13. In a shipping case, a sheet metal body comprising a single blank the margins of 100 which are in a common plane and said blank being bendable on definite lines to produce the several walls of the body, the respective end portions of said blank being in lapping relation at one wall of the body, end members 105 attached to said marginal portions of the body, and a stay strap separate from the body and in contact therewith on a line intermediate the end members, the end portions of said strap passing through said lapping portions of the blank composing the body.

14. In a shipping case, a sheet metal body comprising a single blank the margins of which are in a common plane and said blank 115 being bendable on definite lines to produce the several walls of the body, the respective end portions of the blank being in lapping relation and producing the top member of said case, and a stay the end portions of 120 which are attached to the top-forming portions of the case, said stay being separate from the body and positioned in contact therewith intermediate the ends of said body.

15. In a shipping case, a sheet metal body composed of a single blank the marginal portions of which are in a common plane, said blank being bendable for the respective end portions to occupy a lapping relation, 130

- end members attached to said marginal portions of the body, and a stay the end portions of which pass through said lapped portions of the blank composing the body.
- 5 16. In a shipping case, a sheet metal body composed of a single blank the marginal portions of which are in a common plane, and the end portions of which are slotted and positioned inlapping relation to secure
- 10 registration of said slots, end members attached to said marginal portions of the body, and a stay member in contact with the
- body interiorly thereof, the end portions of said stay member passing through the slotted end portions of the blank composing 15 said body.

In testimony whereof I have signed my name to this specification in the presence of two subscribing witnesses.

SPENCER C. CARY.
